UNITED STATES PATENT OFFICE.

OLIVER C. PENDLETON, OF NEW YORK, N. Y.

RIVETING-MACHINE.

No. 858,751.

Specification of Letters Patent.

Patented July 2, 1907.

Application filed August 3, 1905. Serial No. 272,462.

To all whom it may concern:

Be it known that I, OLIVER C. PENDLETON, residing in the borough of Brooklyn, county of Kings, city and State of New York, have invented certain Improvements in Riveting-Machines, of which the following is a specification.

My invention relates generally to riveting machines, and as herein embodied is designed to produce a machine of this class in which the work is assembled and held in clamped relation during the subsequent operation of heading up the rivets, which is ordinarily done by hand. Such a machine is adapted particularly for sheet metal or other light work and consists essentially of means for holding and spacing a series of rivets in definite relation, together with a series of anvils arranged adjacent to the rivet holders and requisite work clamping devices coöperating with the anvils.

The accompanying drawings will serve to illustrate mechanism suitable for carrying my invention into effect. I do not wish to be understood, however, as limiting myself to either the exact construction or arrangement of parts shown, as various changes may be made therein, without departing from the spirit and scope of my invention.

In the drawings, Figure 1 is a view in front elevation of a machine constructed in accordance with my invention, the lower portion of the table or bench, the foot treadle etc. being broken away. Fig. 2 is a side view thereof. Fig. 3 is a detail cross sectional view of the arm or support for the rivet holders. Fig. 4 is a detail plan view thereof. Fig. 5 is a detail perspective view of the work clamping device and Fig. 6 is a detail view of a portion of the bar carrying the rivet holders.

Referring now to the drawings, 1 represents a table, 35 bench or other support, upon which is mounted a right angular arm 2, preferably of cast iron. The horizontally disposed portion of the arm is grooved, as indicated at 3, to receive a bar 4, preferably of steel. The bar 4, completely fills the groove, being flush with the 40 upper surface of the arm, as shown, and is cut away at equi-spaced points to provide a series of depressions 5, in each of which a spring clip 6, is secured. The clips 6, are provided at their free ends with notches 7 to receive the rivets 8, which are placed therein with their 45 heads under the clips and the shanks thereof projecting upward through the notches.

The high portions 9 of the bar between the rivet holders, serve as anvils and coöperating therewith there are a series of work clamping devices in the form 50 of notched guide fingers 10, carried by a common support 11, which is trunnioned in bearings 12, or may be otherwise mounted, if desired. The support 10 is given motion by means of a foot treadle 13, which is connected therewith by rods 14. A retractile spring 15, secured 55 at one end to the under side of the bench and at the

opposite end to the treadle, acts through the rods 14, to normally hold the work clamping devices elevated, as shown in full lines in Figs. 1 and 2.

The operation of the machine is as follows: In making up sheet metal piping for example, blanks cut to a definite size are first punched to provide a series of spaced rivet holes along opposite edges thereof and are then bent up into cylindrical form with the punched edges overlapping and the openings therein registering. The pipe sections thus blanked and formed, are completed in the riveting machine in the following manner: The sections are slipped upon the arm 2, as indicated by dotted lines in Fig. 2, and adjusted as required to bring the openings therein in line with the rivets, the shanks of which by a slight pressure, are forced through the same. Thus assembled, a slight endwise movement of the pipe section serves to shift the rivets on to the anvils and the operator by pressing upon the treadle brings the clamping devices into action, with the notched ends thereof in line with the projecting rivet shanks. The rivets are then headed up in the usual manner by means of a suitable tool and hammer.

I may dispense with the preliminary punching of the blanks and force the rivets through the metal after assembling and clamping the section in the machine by the first blow of the hammer in upsetting the heads. I have found, however, that this method, while effecting a slight saving in time and labor, does not produce good results as it tends to distort the metal and open the joint.

Having, therefore, described my invention, I claim:

1. A riveting machine comprising a support having a series of depressions formed therein, and a rivet holder in each depression.

2. A riveting machine comprising a supporting bar 90 having a series of depressions formed therein, a rivet holder in each depression, and a co-operating work clamping device.

3. A riveting machine comprising a channeled support, a bar fitted in the channel thereof and having a series of 95 depressions formed therein, and a rivet holder in each depression.

4. A riveting machine comprising a channeled support, a bar fitted in the channel thereof and having a series of depressions formed therein, a rivet holder in each depression, and a co-operating work clamping device.

5. A riveting machine comprising a support having a series of depressions formed therein, a rivet holder in each depression, a series of work clamping fingers, a support common to the several fingers, and means for giving 105 the support motion to move the fingers into and out of clamping relation with the work.

6. A riveting machine comprising a supporting bar having a series of depressions formed therein, a rivet holding clip in each depression, a series of work clamping fingers, a support common to the several fingers, and means for moving the fingers into and out of clamping 110 relation with the work.

7. A riveting machine comprising a bar having a series of projecting portions serving as anvils, a series of rivet 115

- holders secured to the bar in alternating relation to the anvils, a work clamping device co-operating with each anvil, and a support common to the several work clamping devices.
- 5 8. A riveting machine comprising a bar having a series of projecting portions serving as anvils, a series of rivet holders secured to the bar in alternating relation to the anvils, a work clamping device co-operating with each anvil, a support common to the several clamping devices, and spring retracted means for giving said support motion.
9. A riveting machine comprising a supporting bar provided with a series of depressions alternating with a series of anvil portions, the bottom of the depressions being inclined upwardly and merging into the raised anvil portions, and a rivet holding clip in each depression.
10. A riveting machine comprising a support having a series of depressions formed therein, and a separate and independent rivet holding device in each depression.
- 15 11. A riveting machine comprising a support having a series of depressions formed therein, and a device in each depression for holding a rivet to permit free movement thereof in one direction only.
12. A riveting machine comprising a support having a series of depressions formed therein, and a fixed rivet 25 holder in each depression.
13. A riveting machine comprising a support having a series of depressions formed therein, and means fixed in each depression for yieldingly holding a rivet.
14. A riveting machine comprising a support having a 30 series of depressions formed therein, a series of separate and independent rivet holders, and means for securing a rivet holder in each depression.
- In testimony whereof, I affix my signature, in the presence of two witnesses.

OLIVER C. PENDLETON.
